UNITED STATES PATENT OFFICE

2,493,201

PRESSING IRON HOLDER

Harry G. Lautenschlager, Cincinnati, Ohio

Application October 2, 1947, Serial No. 777,382

4 Claims. (Cl. 248—117.2)

1

The invention relates to holders for pressing irons commonly called sad irons such as are used in laundries, dry cleaning establishments and for pressing work in factories where clothing is made.

It is the object of my invention to provide a sad iron stand for receiving the flat pressing surface of the sad iron which will have heat resistant elements arranged to carry the weight of the sad iron out of contact with the cast metallic surface of the holder which would be likely to be softened by exposure to the heat of the iron.

It is a further object of my invention to provide a light and sturdy sad iron holder which will have replaceable parts so that in the event the holder is broken all that is required is to purchase new uprights or other parts and repair the holder, so that it will not be necessary to purchase an entire new holder or stand, or to have metal welded on to the stand to repair it.

Sad irons are provided with various ways of keeping them hot. They are quite heavy and are usually kept at a sufficient heat so that unless they are placed on a holder or stand they will damage the fabric of the pressing board, or of garments being pressed. Ordinarily the irons have been supported on a low stand which is a constant fire hazard because when the iron is on the low stand its heat is likely to cause ignition of any wooden support on which the stand may be placed. It is my object to eliminate this fire hazard and at the same time to greatly reduce the labor of lifting the iron by providing a stand with high supporting legs which makes it possible to have the actual iron close to the work.

It is my object to provide a holder or stand which will be light and inexpensive and structurally assembled in such a way that it will be simple to replace broken parts of the construction.

The foregoing objects and other objects which will be described in the ensuing description, I accomplish by that certain combination and arrangement of parts of which I have illustrated a preferred embodiment.

In the drawings:

Figure 1 is a plan view of a preferred combination of parts.

Figure 2 is a sectional view along the lines 2—2 of Figure 1.

Figure 3 is a sectional view along the lines 3—3 of Figure 2.

Figure 4 is a detailed sectional view showing a preferred arrangement for supporting the upper casting of the stand on upright supports.

Referring to the drawings, the sad iron stand or holder consists of an upper casting of light

2

metal such as aluminum, indicated at 1. The upper casting has preferably integrally cast therewith cross bars 2 which substantially subdivide the space 3 in the casting which receives the pressing surface of the sad iron.

The cross bars 2 are provided with grooved portions 4, which receive ribs 5 which have rounded upper surfaces as indicated at 6 and upturned ends 7. The upper surface of the ribs is rounded so as to permit the pressing surface of the sad iron to move freely along on the ribs. The upwardly bent portion 7 (best shown in Figure 3), provides buffers to prevent the surface of the sad iron from bruising or melting the upper surface of the casting 1.

For supporting the ribs 5, pins 8 having screw heads 9, extend up through openings in the cross bars 2, one near each end of the rib. Recessed openings 10 enclose coil springs 11 which urge the ribs 5 upward so that the surface of the sad iron is supported above the upper surface of the cross bars 2.

The cross bars 2 have downwardly depending tongues 12 which fit within channeled portions 13 in upright supports 14. Matching openings are provided in the tongues 12 and the walls of the channels 13, so that tapered pins 15 may be tapped in to hold the uprights 14 rigidly in position supporting the ribs and the flat upper casting.

It will be obvious that in the preferred combination described if one of the legs or uprights 14 becomes broken off, it will be a simple matter to substitute a new leg. If the ribs 5 become worn or the springs 11 lose their resilience, it will be a simple matter to replace either the rib or the spring, it being understood that the pins 8 have threads at their upper ends which are secured in threaded openings in the ribs 5.

It will further be observed that I have provided a sad iron stand which not only is provided with means for preventing injury to the stand itself, but which prevents marring of the surface of the pressing iron.

Having thus described my invention, what I claim as new and desire to secure by Letters Patent is:

1. A sad iron stand having a flat upper casting having an opening for receiving the base of a sad iron and a plurality of bars extending across the opening, grooved portions in said bars, and a heat resistant rib resiliently and detachably mounted in each of said grooved portions and a plurality of upright supports demountably secured to said upper casting.

2. A sad iron stand having a flat upper casting

having an opening for receiving the sad iron and a plurality of bars extending across the opening and formed integrally with said casting, a plurality of grooved bars extending across the opening, each having a grooved portion and a heat resistant rib resiliently and detachably mounted in each grooved portion, and the bars extending across said upper casting having depending tongues, and upright supports having channeled portions to receive said depending tongues demountably attached to said tongues.

3. A sad iron stand comprising a flat casting having an opening for receiving the base of a sad iron, a plurality of bars extending across the opening, a heat resistant rib resiliently mounted on each of said bars for supporting a sad iron out of contact with said casting, said ribs terminating in upstanding projections of a height greater than all portions of the surrounding casting.

20

4. A sad iron stand comprising a flat casting having an opening for receiving the base of a sad iron, a plurality of bars extending across the opening, a heat resistant rib resiliently mounted on each of said bars for supporting a sad iron out of contact with said casting, said bars being grooved and said ribs being mounted within said grooves.
